UNITED STATES PATENT OFFICE.

EDWIN G. LITTLE, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SKATE-OPERATING APPARATUS.

Application filed January 26, 1926. Serial No. 83,912.

My invention relates to railway skate operating apparatus, that is, to apparatus for moving the skate to and from its active position on the rail.

I will describe one form of skate operating apparatus embodying my invention, and will then point out the novel features thereof in claims.

In the accompanying drawing, Fig. 1 is a view, partly in vertical section, showing one form of skate operating apparatus embodying my invention. Fig. 2 is a top plan view showing the trackway skate illustrated in Fig. 1. Fig. 3 is a side view of the skate shown in Fig. 2.

Similar reference characters refer to similar parts in each of the three views.

Referring first to Fig. 1, the reference character A designates a track rail of a railway track. A trackway skate B (see also Figs. 2 and 3) is provided with a channel 1 on its under side to receive the head of the rail A when the skate is in its active position upon the rail. The skate comprises an inclined tongue 2 overlying the head of the rail, and upon which the tread of a car wheel is adapted to run. The tongue 2 merges into a curved surface 4, so proportioned as to fit the rounded surface of the wheel tread and to form an abutment against which the wheel engages. The skate is provided with a channel 5 to receive the flange of the wheel. Outstanding from the lower edge of the skate B is a lug 6, which is inclined downwardly, as best shown in Fig. 1, and the purpose of which will appear hereinafter.

The skate B is arranged to be moved to and from its active position by means of apparatus which I will now describe.

Located in the trackway beside rail A is a housing 7. A lever 8 is pivotally supported in this housing at point 9. The free end of the lever 8 is pivoted at 10 to a movable link 11 provided with a yoke 13 which receives the lug 6 of the skate B. The parts are so proportioned that when the skate is not resting on the rail, the weight of the skate tends to rotate the skate in a clockwise direction, thereby wedging the lug 6 in the yoke 13 and resulting in a gripping action between the skate and the link 11. The free end of link 11 is guided by means of a fixed cam 14 which may be integral

with the housing 7 and which is engaged by a roller 12 pivoted in link 11.

The lever 8 is operated by a motor D, here illustrated as a motor of the fluid pressure type. This motor comprises a cylinder 15 containing a reciprocable piston 16, to which is attached a piston rod 17. The manner of connection of the rod 17 with the piston permits slight oscillation of the rod 17. The free end of this rod is attached to lever 8, and the lever is therefore swung about its pivot 9 when piston 16 is moved in the cylinder 15. Piston 16 is constantly urged toward its left-hand position, in which it is illustrated in the drawing, by means of a spring 18.

The admission of fluid pressure to the cylinder 15 is controlled by a valve E which comprises a valve stem 19 provided with a winding 20 and an armature 19a. When winding 20 is de-energized, valve stem 19 occupies its upper position, so that the left-hand end of cylinder 15 is connected with atmosphere. When winding 20 is energized, however, the stem 19 is moved downwardly and the left-hand end of cylinder 15 is then disconnected from atmosphere and is connected with a suitable source of fluid pressure, usually air, not shown in the drawing.

As illustrated in the drawing, winding 20 of valve E is de-energized, so that the left-hand end of cylinder 15 is connected with atmosphere. Piston 16 therefore occupies its left-hand position under the influence of spring 18. Lever 8 occupies its left-hand position and the parts are so proportioned and arranged that under these conditions the skate B carried by link 11 is retracted to its inactive position, as illustrated in full lines in Fig. 1.

I will now assume that winding 20 of valve E becomes energized. Stem 19 of this valve moves downwardly and air is admitted to cylinder 15 forcing piston 16 to the right against the bias exerted by spring 18. This movement of piston 16 swings lever 8 to the right about its pivot 9. Link 11 is therefore moved toward the right, the motion of the link being guided by the roller 12 on cam 14. During this motion the skate B is lifted toward the rail A. When the pivots 9 and 10 are in approximately a straight line with the roller 12, the skate B overhangs the rail A. As the motion of lever 8 con-

tinues, however, it will be seen that link 11 is twisted slightly in a clockwise direction, thereby dropping the skate B on the head of the rail. The motion of lever 8 is continued for a slight distance past the position in which the skate engages the rail, so that when the parts are in their final positions, as illustrated in broken lines on the drawing, the skate rests upon the rail and the lug 6 is completely disengaged from the link 11, though still projecting into yoke 13. If a car attempts to proceed over rail A with the skate in its active position, the front wheel of the car engages the skate and slides it along the rail, thereby causing a powerful braking effect and bringing the car to rest. This operation of the skate of course moves it with respect to the link 11, but the lug 6 on the skate, being free in the yoke 13 of the link, moves out of the yoke without interfering with the operating apparatus in any way. After the skate has been engaged by a car, it may be returned by an attendant to a position in which the lug 6 enters yoke 13.

Assuming that the skate is in its active position, it may be returned to its inactive position by de-energizing winding 20 of valve E. This operation interrupts the supply of air to the cylinder 15 and connects the cylinder with atmosphere. Spring 18 then returns piston 16 to its left-hand position. The first part of the resulting motion of lever 8 to the left twists link 11 slightly in a counter-clockwise direction, thereby causing lug 6 on the skate to be gripped in the yoke 13 of the link. As the motion of lever 8 continues, the skate B is lifted from its position on the rail and is carried downwardly till the parts are all returned to their original positions.

During the return of the skate from its active to its inactive position, it will be seen that the weight of the skate and the link 11 have a tendency to aid the spring 18 in restoring the parts to the position in which they are illustrated in full lines in the drawing. In the absence of any preventative means the parts would return sharply and would be suddenly arrested at the ends of their strokes by engagement of the piston 16 with the end of the cylinder. In order to prevent the mechanical shock which would result from this undesirable occurrence I provide a valve G between valve E and the cylinder 15. This valve G comprises a flexible diaphragm 21 carrying a valve seat 22. The diaphragm and seat are provided with a hole 25 which receives a fixed valve stem 23 with considerable clearance. When air is being admitted to the cylinder, this air flows through the hole 25 around the stem 23 and meets with substantially no opposition. During the return of the piston 16 to its left-hand position how-

ever, the exhaust air which is driven from the cylinder is under considerable pressure, and this air moves diaphragm 21 to the left and brings the valve seat 22 into engagement with the head of the stem 23. As a result the passage from the cylinder is substantially reduced and there is a cushioning effect which retards the motion of the parts as the skate is returned to its inactive position.

In the form here shown the skate normally occupies its inactive position and is moved to its active or braking position by the motor but it should be pointed out that this particular construction is not essential to my invention.

Although I have herein shown and described only one form of skate operating apparatus embodying my invention, it is understood that various changes and modifications may be made therein within the scope of the appended claims without departing from the spirit and scope of my invention.

Having thus described my invention, what I claim is:

1. Railway skate operating apparatus comprising a movable link for detachably engaging the skate, means for operating said link to move the skate to and from its active position, and a fixed cam member for guiding said link.

2. Railway skate operating apparatus comprising a movable link provided with a yoke for freely receiving said skate, the skate being at times clamped in said yoke by its own weight, and means for operating said link to move said skate to its active position.

3. Railway skate operating apparatus comprising a movable skate actuating link, means for moving one end of said link along a predetermined path, and a cam for guiding the other end of the link.

4. Railway skate operating apparatus comprising a movable link for detachably gripping the skate and normally occupying a position in which the skate is removed from the rail, and means for at times moving the link to a second position in which the skate rests upon the rail and is detached from the link.

5. Railway skate operating apparatus comprising a pivoted lever, a movable link for detachably gripping the skate and having one end pivotally attached to the free end of said lever, a cam for guiding the other end of said link, and means for operating said lever whereby said skate is moved to and from its active position on the rail.

6. Railway skate operating apparatus comprising a movable link for detachably gripping the skate and normally occupying a position in which the skate is removed from the rail, a pivoted lever having its free end attached to one end of said link,

a cam for guiding the other end of said link and a fluid pressure motor for at times operating said lever to move the skate to its active position.

5 7. Railway skate operating apparatus comprising a fluid pressure motor, a valve for controlling said motor, linkwork for operatively connecting said motor with a skate, and a fixed cam for guiding said linkwork.

10 8. Railway skate operating apparatus comprising a fluid pressure motor arranged when operated to move said skate to its active position, the skate being biased to its inactive position, a normally open valve

15 responsive at times to the pressure in said motor, and means for at times supplying fluid pressure to said motor through said valve and for at other times connecting said motor with atmosphere through said valve.

20 9. Railway skate operating apparatus comprising means for constantly urging the skate toward its inactive position, a fluid pressure motor arranged when operated to move the skate to its active position, a first

25 valve for at times supplying fluid pressure to said motor and for at other times con-

necting said motor with atmosphere, and a second valve responsive at times to the pressure in said motor and interposed between the motor and said first valve.

30 10. Railway skate operating apparatus comprising means for constantly urging the skate toward its inactive position, a fluid pressure motor arranged when operated to move the skate to its active position, a first valve for at times supplying fluid pressure to said motor and for at other times connecting said motor with atmosphere, and a second valve interposed between said first valve and said motor and comprising a fixed valve stem 35 and a flexible diaphragm having a seat co-operating with said stem.

11. Railway skate operating apparatus comprising a link detachably connected with the skate, a motor for actuating said link, and a cam for guiding the link so that when the motor is operated the link places the skate upon the rail and detaches the link from the skate.

In testimony whereof I affix my signature.

EDWIN G. LITTLE.
